US0D1089164S

(12) **United States Design Patent** (10) **Patent No.:** **US D1,089,164 S**
(45) **Date of Patent:** ** *Aug. 19, 2025

(54) **PROTECTIVE CASE FOR A COMPUTING DEVICE**

(71) Applicant: **Urban Armor Gear, LLC**, Laguna Niguel, CA (US)

(72) Inventors: **Evan Hong**, Murrieta, CA (US); **Eric Yoshinari**, Laguna Niguel, CA (US)

(73) Assignee: **Urban Armor Gear, LLC**, Laguna Niguel, CA (US)

(*) Notice: This patent is subject to a terminal disclaimer.

(**) Term: **15 Years**

(21) Appl. No.: **29/907,007**

(22) Filed: **Jan. 3, 2024**

(57) **CLAIM**

The ornamental design for a protective case for a computing device as shown and described.

DESCRIPTION

FIG. 1 is a rear, top, and side perspective view of a protective case for a computing device showing our new design;

FIG. 2 is a front elevational view thereof;

FIG. 3 is a rear elevational view thereof;

FIG. 4 is a side elevational view thereof;

FIG. 5 is an opposite side elevational view thereof;

FIG. 6 is a top plan view thereof; and,

FIG. 7 is a bottom plan view thereof.

The broken lines in the drawing figures form no part of the claimed design, and they illustrate portions of the protective case for a computing device that form no part of the claimed design.

1 Claim, 5 Drawing Sheets
